(57) **CLAIM**

We claim the ornamental design for a portable vehicle connectivity device, substantially as shown and described.

DESCRIPTION

FIG. 1 is a top front right side isometric view of a portable vehicle connectivity device.

FIG. 2 is a bottom rear left side isometric view of the portable vehicle connectivity device of FIG. 1.

FIG. 3 is a front elevation view of the portable vehicle connectivity device of FIG. 1.

FIG. 4 is a rear elevation view of the portable vehicle connectivity device of FIG. 1.

FIG. 5 is a left side elevation view of the portable vehicle connectivity device of FIG. 1.

FIG. 6 is a right side elevation view of the portable vehicle connectivity device of FIG. 1.

FIG. 7 is a top plan view of the portable vehicle connectivity device of FIG. 1; and,

FIG. 8 is a bottom plan view of the portable vehicle connectivity device of FIG. 1.
